ADOLPH FUHLENDORF AND JACOB GROTHE, OF NEW YORK, N. Y., ASSIGNORS TO WALTER W. RAMER, OF NEW YORK, N. Y.

RIBBON SHIFTING AND RETAINING MECHANISM.

No. 861,211.

Specification of Letters Patent.

Patented July 23, 1907.

Application filed October 30, 1906. Serial No. 341,225.

To all whom it may concern:

Be it known that we, ADOLPH FUHLENDORF and JACOB GROTHE, citizens of the United States, residing at New York city, New York, have invented certain new and useful Improvements in Ribbon Shifting and Retaining Mechanism, of which the following is a specification.

The present invention relates to ribbon shifting and retaining mechanism for typewriters and is directed to 10 means for bringing any part of a multicolor or poly-chrome ribbon of a typewriter over the type thereof and retaining the ribbon in its shifted position.

In general terms the invention includes means for reciprocating the ribbon guide of a typewriter and also 15 means for retaining or locking the ribbon guide in its shifted position.

One object of the invention is to produce a device 20 which is extremely simple in construction and operation and consequently may be cheaply produced. A further object is to present a construction wherein the fewest parts possible consistent with efficient operation are contained, and a further object is so to construct the invention that it may readily be attached to a typewriter, if need be by an inexperienced operator, 25 and work satisfactorily.

The accompanying drawing illustrates the preferred embodiment of the invention, and in the drawing Figure 1 is a top plan view of a typewriting machine with part of the upper plate and the carriage removed, and 30 having the ribbon shifting mechanism attached. Fig. 2 is a top plan view of the portion of the typewriter to which the shifting mechanism is attached, the latter in this figure being shown as shifted and held in its shifted position. Fig. 3 is a side elevational view of the 35 proved ribbon shifting mechanism; and Fig. 4 is a perspective view of a slotted clamp employed in connection with the invention.

Having reference to the drawing 1 represents the top plate of a typewriting machine, supplied with the usual 40 shifting rod 2 and guide rod 3. Resting upon the bed plate 1 is the ribbon guide 4, which is displaceable horizontally within defined limits by the links 5 and 6, the former being mounted upon the post 7 and extending to a lug 8 upon the lower face of the ribbon guide, and the 45 link 6 being mounted upon a post 9 and being secured at 10 upon the lower face of the ribbon guide. It will be understood that the links at both ends are mounted to have pivotal action about their supports to permit of the ribbon guide being easily reciprocated. The elements so far described, while being adjuncts to our invention, are not comprised therein, but are present in 50 all typewriting machines of certain makes.

It is the purpose of our invention to do away with the complicated and expensive devices, now employed

in shifting ribbons to bring any desired part of a poly-chrome ribbon over the type of a typewriting machine, and to this end we mount upon the post 9, above referred to, or at any other suitable place, a lever 11, which is bifurcated at one end and terminates in jaws 12, 13 which are held together by the screw 14 or a similar retaining element. This lever serves to shift the ribbon guide and will be referred to as the shift lever hereinafter.

Substantially intermediate its length the shift lever 11 is provided with lugs 15 between which a second 65 shorter lever (called the locking lever) 16 is pivoted upon a pin 17. The lever 16 is preferably tapered at one end to form a wedge shaped point 18, which is made of casehardened material, and is designed to enter the slot 19 of a clamp 20 which, as shown in Fig. 2 70 of the drawing, may be snapped upon the post 21 or other convenient part of the machine. The clamp 20 is provided with a small extension 22 which serves as a handle when mounting the clamp upon the post. Between the arms of the levers 11 and 16 is provided a 75 small pin 23 encircled by a spiral spring 24 which has a normal tendency to press the lever 16 away from the lever 11 and thus causes the forward end of the lever 16 to spring against the lever 11 when the point 18 is released from the slot 19 in a manner hereinafter described. It will be noted that the lever 11 is longer than the lever 16 and extends a short distance beyond the end of the machine plate 1, to facilitate manipulation thereof by an operator.

Entering the side of the lever 11 is a set screw 25 85 surrounded by a spring 26 and carrying a knurled nut 26^a. The set screw 25 is provided to adjust the distance which the lever 11 need or may be moved to bring either the part 27 or the part 28 of the typewriter ribbon over the type, it being assumed that the two 90 parts of the ribbon are of different colors.

In securing the attachment to the machine the jaws 12 and 13 are placed about the post 9. The screw 14 is then tightened sufficiently to hold the lever 11 in place but is not screwed home. The lever 16 is then 95 pulled outwards in a direction away from the machine until the point 18 enters the slot 19. The proper relative positions of the levers having thus been found the screw 14 is driven home. It will be understood that the knurled nut 26^a regulates the area of colored ribbon *e. g.* that designated 27, that is presented to the type. If the nut 26^a is screwed closely against the plate 1 of the machine, the ribbon guide 4 will have very little backward movement in the direction of the shifting rod 2 and thus substantially the entire width 100 of the ribbon part 27 will be available. Screwing the knurled nut 26^a closer to the screw head of screw 25 105 will give the lever 11 greater range of movement and

consequently narrow the available working space of ribbon part 27, of course, however, always leaving enough to span the width of one letter when the mechanism is in the position illustrated in Fig. 2.

5 The operation of the invention which is very simple is as follows:—Assuming that 28 represents an ordinary black or blue ribbon and the operator desires to bring out a word or sentence for example in red, she presses upon lever 16 until point 18 drops into slot 19, whereby 10 ribbon part 27, which may be assumed to be red, is brought over the type and while the operator is writing, the red part of the ribbon is firmly retained in place. When the operator desires to resume the use of the ordinary ribbon she simply presses the lever 11 15 outwardly thus tripping the point 18 out of the slot 19, the spring 24 forcing the lever 16 out of reach of the slot 19 and permitting the parts to resume their initial position.

It will be noted from the foregoing description that 20 the invention is extremely simple, easy of attachment and operation and is very positive in action.

Having thus described our invention, what we claim as new and desire to secure by Letters Patent is:—

1. In a device of the character described, the combination 25 of a ribbon guide, a shift lever adapted to reciprocate the same, a locking lever associated with and pivoted at an intermediate point of said shift lever and a spring clamp for retaining said locking lever after the ribbon guide has been reciprocated, substantially as described.

30 2. In a device of the character described, the combination of a ribbon guide, a shift lever designed to reciprocate the same, a link extending between said ribbon guide and shift lever and having pivotal action at each point of attachment, a locking lever united with said shift lever 35 and being adapted to lock the ribbon guide in its shifted position, and a spring clamp into which the locking lever is adapted to enter, substantially as described.

3. In a device of the character described, the combination 40 of a ribbon guide, a shift lever adapted to reciprocate the same, a locking lever having a tapered point integral therewith, secured to said shift lever, and a spring clamp for engaging the tapered end of said locking lever, substantially as described.

4. In a device of the character described, the combination 45 of a ribbon guide, a shift lever adapted to reciprocate the same, means upon said shift lever for limiting the range of movement of said ribbon guide, a locking lever pivoted at a point intermediate the ends of said shift lever for retaining said ribbon guide when shifted, and a spring clamp into which the end of said locking lever is adapted 50 to enter, substantially as described.

5. In a device of the character described, the combination 55 of a ribbon guide, a post upon which a shift lever having a bifurcated end is mounted, a link connecting said ribbon guide and shift lever, a locking lever pivoted to and movable in a horizontal plane with said shift lever for retaining the ribbon guide when shifted, and a spring clamp into which the end of said locking lever is adapted to enter, substantially as described.

60 6. In a device of the character described, the combination of a ribbon guide, a shift lever adapted to reciprocate the same, a locking lever for retaining said ribbon guide when shifted and means to engage said locking lever, said means comprising a spring clamp having a slot into which the end of said locking lever projects, substantially as described.

7. In a device of the character described, the combination 70 of a ribbon guide, a shift lever adapted to reciprocate the same, a locking lever pivoted between lugs extending from the shift lever for retaining the ribbon guide when shifted, and means for limiting the range of movement of said ribbon guide, said means comprising a screw entering the side of the shift lever at right angles thereto, a knurled nut displaceable upon the screw and a spring encircling the 75 screw, substantially as described.

8. In a device of the character described, the combination of a ribbon guide, a shift lever for operating said ribbon guide, a link connecting the said lever and ribbon guide, a locking lever pivoted between lugs formed integrally with said shift lever intermediate its ends, and a spring clamp for retaining said locking lever when the ribbon guide has been shifted by means of said shift lever, substantially as described.

9. In a device of the character described, the combination of a ribbon guide, a link attached near each edge of said guide, a shift lever adapted to reciprocate said guide horizontally, one of said links connecting said shift lever with the said ribbon guide, a locking lever pivoted between lugs extending from the sides of said shift lever, a spring interposed between said levers and having a normal tendency to force the shorter end of said locking lever against said shift lever, means upon said shift lever for limiting the range of movement of said ribbon guide, and means for retaining said locking lever when the ribbon guide has been shifted, said means comprising a spring clamp having a handle and a slot therein, the end of said locking lever being adapted to enter the slot in said clamp, substantially as described.

10. In a device of the character described, the combination with a typewriter of a ribbon guide displaceable 100 thereon horizontally, a shift lever fulcrumed to operate in a horizontal plane a link connected to and extending from the ribbon guide to the fulcrum of the shift lever, whereby the ribbon guide may be shifted by the operation of said shift lever, and a spring clamp adapted to receive the end 105 of the locking lever, substantially as described.

11. In a device of the character described, the combination with a typewriter of a ribbon guide displaceable horizontally upon the top plate thereof, a shift lever fulcrumed upon a post and adapted to have pivotal action thereabout in a horizontal plane, a link connection between the ribbon guide and shift lever, a locking lever designed to lock the ribbon guide in shifted position, and a spring clamp adapted to receive the end of the locking lever, substantially as described.

115 12. In a device of the character described, the combination of a shift lever movable in a horizontal plane, a ribbon guide operable through the medium of said shift lever, a locking lever associated with, and movable in the same plane as said shift lever, and a spring clamp adapted to 120 receive the end of said locking lever, substantially as described.

13. In a device of the character described, the combination of a shift lever movable in a horizontal plane, a post upon which the shift lever is fulcrumed, a ribbon guide, a link extending from the ribbon guide to the post, a locking lever for retaining the ribbon guide in shifted position after the same has been moved by the shift lever, and a spring clamp adapted to receive the end of the locking lever, substantially as described.

125 14. In a device of the character described, the combination of a shift lever movable in a horizontal plane, a ribbon guide operable through the medium of said shift lever, a locking lever associated with, and movable in the same plane as, said shift lever, and a slotted spring clamp adapted to be engaged by the locking lever when the ribbon guide has been shifted, substantially as described.

135 15. In a device of the character described, the combination with a typewriter, of a shift lever mounted on a post thereof, and adapted to move in a horizontal plane, a ribbon guide, a link extending from the ribbon guide to said post, means for limiting the range of movement of the shift lever about its fulcrum, and a spring clamp adapted to receive the end of the locking lever, substantially as described.

140 16. In a device of the character described, the combination with a typewriter, of a shift lever mounted on a post thereof, a ribbon guide operable through the medium of said shift lever, a locking lever associated with said shift lever, and a spring clamp removably mounted on a second 150 post of said typewriter, said spring clamp having a slot into which the end of said locking lever is adapted to enter when the ribbon guide has been shifted, substantially as described.

17. In a device of the character described, the combina-

155

tion with a typewriter of a shift lever movable in a horizontal plane, a ribbon guide operable through the medium of said shift lever, ears formed on said shift lever, a locking lever pivoted in said ears and adapted to move in the same plane as the shift lever, and a spring clamp adapted to receive the end of said locking lever, substantially as described.

18. In a device of the character described, the combination with a typewriter of a shift lever movable in a horizontal plane, a ribbon guide operable through the medium of said shift lever, ears formed on said shift lever, a locking lever pivoted in said ears, a spring clamp for engaging

said locking lever and a spring interposed between said levers and having a normal tendency to force the locking end of the locking lever away from the engaging means, substantially as described.

In testimony whereof we have affixed our signatures in presence of two witnesses.
